INTEGRALLY HINGED WEATHERPROOF RECEPTACLE COVER

Lawrence P. Mellyn, Glocester, R.I., assignor to General
Electric Company, a corporation of New York

Filed Aug. 31, 1966, Ser. No. 3,668

Term of patent 14 years

(Cl. D26—13)

Fig. 1.

Fig. 3.

Fig. 2.

Fig. 5.

Fig. 4.

FIG. 1 is a front perspective view of an integrally hinged weatherproof receptacle cover embodying my new design;
 FIG. 2 is a front elevational view thereof;
 FIG. 3 is a top elevational view thereof;
 FIG. 4 is a bottom elevational view thereof; and
 FIG. 5 is a side elevational view thereof.

I claim:

The ornamental design for an integrally hinged weatherproof receptacle cover, as shown.
